UNITED STATES PATENT OFFICE

2,494,555

CENTERLESS GRINDING MACHINE

George E. Hieber, Waynesboro, Pa., assignor to
 Landis Machine Company, Waynesboro, Pa., a
 corporation of Pennsylvania

Application December 3, 1946, Serial No. 713,795

18 Claims. (Cl. 51—103)

1 This invention relates to centerless grinding machines and in particular to grinding machines of the centerless type in which the regulating or control wheel performs certain feeding and ejecting functions in addition to controlling the rotation of the work piece in the grinding throat formed between the opposed peripheral surfaces of the control and grinding wheels.

The invention is an improvement over the manually operable type of machine shown and described in the copending application of Arthur Scrivener, Serial No. 556,426, filed September 29, 1944, now Patent No. 2,427,024, issued September 9, 1947.

While the Scrivener invention is quite efficient for many operations, the removal of a large amount of metal from the work piece is made difficult by reason of the tendency of the grinding wheel to impart a high rotational speed to the work piece. This is transmitted to the control wheel, creating a strong torque which it is difficult for the operator to control by means of the operating handle. Consequently, the use of the Scrivener invention is restricted in respect to the amount of metal to be removed from the work piece.

Accordingly it is an object of this invention to provide means for controllably absorbing the reactionary torque force transmitted from the grinding wheel to the control wheel during the grinding operation.

It is another object of the present invention to provide means for controllably absorbing the torque force transmitted to an oscillating control wheel during the grinding operation, while nullifying the controlling effect of said means during the return stroke of the control wheel.

A further object of the invention is to employ fluid means to facilitate the manual operation of an oscillating control wheel with uniform rapidity of such operation in grinding operations of varied severity.

It is also the purpose of the invention to provide mechanism as above characterized comprising an extremely compact arrangement of structurally simple elements which will be highly efficient in functional operation and which will not retard the operational speed of the machine nor interfere, by virtue of its location, with the functions of other parts of the machine.

Further objects and advantages will be apparent from a consideration of the following description and the accompanying drawings.

2 which illustrate a preferred embodiment of the invention.

In the drawings, wherein like reference characters designate corresponding parts throughout the several views:

Figure 1 is a partial front elevation of the machine showing the control wheel positioned relative to the work support at an intermediate stage of the grinding operation;

10 Figure 2 is a fragmentary horizontal sectional view taken along line 2—2 of Figure 1; and

Figure 3 is a fragmentary vertical sectional view taken substantially on line 3—3 of Figure 2.

Referring to Figure 1, a part of a main slide member 20 of a centerless grinding machine is shown. A work rest supporting mechanism 22 is mounted upon main slide 20. The mechanism 22 may be similar to that shown and described in the copending application of C. W. Hopkins,

20 Serial No. 571,518, filed January 5, 1945, now Patent No. 2,417,413, issued March 18, 1947. A work rest blade 24 is supported in the grinding throat by the mechanism 22. A motor driven grinding wheel 26 having thread grinding ribs on its peripheral surface is supported by the base of the machine (not shown) adjacent to work rest blade 24 to effect abrading action upon a work piece W placed on an inclined top surface 28 thereof.

30 Any conventional means may be used to adjust the main slide 20 together with the work rest mechanism 22 in a direction perpendicular to the axis of the grinding wheel 26 in order to position the work rest blade 24 at the proper distance from said grinding wheel. An auxiliary slide 30 is mounted on main slide 20 and supports a housing 32. A control wheel 34 is supported, by means later to be described, in the housing 32.

35 Any conventional means may be employed to adjust slide 30, housing 32 and control wheel 34 in a direction perpendicular to the axis of grinding wheel 26 in order to provide a grinding throat of the proper width between

40 grinding wheel 26 and control wheel 34.

45 A control wheel spindle 35 is mounted at each end in the usual manner on suitable bearing 37 in a bore 36 in housing 32. A cap member 38, secured by screws 40 to housing 32 at the forward end of bore 36 and surrounding spindle 35, is employed to retain said spindle and its bearings in bore 36. Forwardly of cap member 38, spindle 35 is formed with a reduced diameter tapered portion 42. Mounted upon portion 42, a wheel supporting member 44 is restrained

50 55

50 A control wheel spindle 35 is mounted at each end in the usual manner on suitable bearing 37 in a bore 36 in housing 32. A cap member 38, secured by screws 40 to housing 32 at the forward end of bore 36 and surrounding spindle 35, is employed to retain said spindle and its bearings in bore 36. Forwardly of cap member 38, spindle 35 is formed with a reduced diameter tapered portion 42. Mounted upon portion 42, a wheel supporting member 44 is restrained

3

against axial movement by a cap screw 46 threadedly engaged in the forward extremity of spindle portion 42 and having a flange 48 which engages the bottom of a counterbore 50 in the forward end of the wheel supporting member 44.

At its rear end, member 44 is formed with a diametrically enlarged portion 52 provided with an external annular flange 54. The part 52 of the member 44 is fitted within one end of the central circular opening 56 of the control wheel 34 with the flange 54 in abutting contact against the adjacent side face of the wheel. An annular member 58 is telescopically fitted over the other end of the member 44 and within the opposite end of the opening 56 of the control wheel, said member having the flange 60 for abutting contact against the front face of said wheel. This member 58 is connected with the part 52 of member 44 by means of the cap screws 62 having threaded connection with said part 52 and whereby the members 44 and 58 are rigidly connected against relative rotation and with their flanges 54 and 60, respectively, in tight clamping contact with the opposite side faces of control wheel 34.

Forwardly adjacent flange 48 of screw 46, a bushing 64 is secured in bore 50 of member 44 by

4

82 in exact alignment with the axis of wheel spindle 35. A short shaft 84 is mounted in bore 82 on bushing 86 and needle bearing 88. The rearward end of bore 82 is closed by the sealing member 90. To the rearward end of shaft 84 is secured a radially extending clutch dog 92 for selectively engaging one of the slots 68 in the forward face of member 44, thus providing a driving connection between shaft 84 and control wheel 34. It will be apparent that the reason for such selectivity is to bring any one of the pockets 76, 78 or others of control wheel 34 into proper work-receiving position relative to work rest 24.

The forward end of shaft 84 is provided with a transverse rectangular groove 94 in which is seated one end of an operating lever 96, said lever being secured to shaft 84 by means of screws 98. The forward surface of cover member 10 is provided with an arcuate T-slot 100 having its center of curvature coincident with the axis of shaft 84. A pair of T-shaped blocks 102 are seated in T-slot 100 and are provided with tapped holes for threaded engagement by cap screws 104 which retain stop lugs 106 against the forward surface of cover member 10. Thus it is evident that stop lugs 106 may be secured in any desired spaced relation to each other between the ends of T-slot

connection between control wheel 34 and operating lever 96 exists.

As shown in Figure 2, shaft 84 is formed as a spur pinion 134 for part of its length. As shown in Figure 3, a cylindrical member 136 is mounted in a bore 138 which in the present case, passes diagonally through the cover member 70. Member 136 has an intermediate semi-cylindrical section provided along its flat side with rack teeth 140 which are in constant mesh with the pinion 134. The upper end of bore 138 is closed by a welch plug 142 while the lower end is closed by a gasket 144 and cover plate 146 which are secured to cover member 70 by means of screws 148. The lower end of member 136 is surrounded by a series of hydraulic packing elements 150 of leather or other suitable material. This packing 150 is retained in place by a washer 152 and lock-nuts 154 which are threadedly engaged on the extremity of member 136. Thus, bore 138 and member 136 comprise a hydraulic cylinder-and-piston combination. It will be seen in Figure 3 that cover plate 146 which closes one end of the cylinder 138, is provided with a recess 156 into which lock nuts 154 extend at the extreme downward travel of piston 136.

The interior of cover member 70 is voided as seen in Figures 2 and 3 to form a large oil reservoir 158. Near the top of reservoir 158 a passage 160 is provided, connecting said reservoir 158 with the cylinder 138. The bottom end of cylinder 138 is connected by a channel 162 to a passage 164 which is provided with a seat for a valve 166. Above the valve 166, passage 164 communicates with the reservoir 158. Valve 166 is provided with a downwardly extending cylindrical portion 168 which is utilized to retain one end of a coil spring 170, the opposite end of which is held in position by a pin 172, frictionally mounted in cover plate 146. Spring 170, being held in compression between cover plate 146 and valve 166, serves to urge the valve against its seat and thereby fluid is prevented from leaving the lower end of cylinder 138 and passing through passage 164 to reservoir 158. On the other hand, a drop in fluid pressure in the lower end of cylinder 138 will result in valve 166 being drawn downwardly away from its seat, compressing spring 170 and permitting fluid from reservoir 158 to pass through passage 164 and channel 162 into cylinder 138.

Another cylindrical opening 174 is formed in the wall of cover member 70 and communicates with passage 164 at the outer side of valve 166. A metering valve seat member 176, having a portion 178 of its interior threaded, is mounted in opening 174, being retained therein by the member 180 which is threadedly engaged in the end of opening 174. Suitable packing 182 is inserted between members 176 and 180 to prevent the escape of fluid from cover 70.

A valve stem 184 is threadedly engaged with portion 178 of valve seat member 176 and has a portion 186 of reduced diameter extending coaxially within said member toward cylinder 138. A valve orifice 188 is formed at the inner end of seat member 176, while the valve stem portion 186 terminates in a tapered needle point. This tapered portion 190 cooperates with valve orifice 188 to form a metered passage for the hydraulic fluid, the effective area of said passage being selectively variable by advancing or withdrawing valve stem 184. This is done by manual rotation of a knob 192 affixed to the protruding end of stem 184. The threaded engagement between

stem 184 and seat member 176 causes stem 184 to be moved in the desired direction. In this manner, the amount of fluid leaving the lower end of cylinder 138 and hence the hydraulic resistance to downward movement of member 136 may be controlled.

A radial opening 194 is formed in the wall of seat member 176 and provides a connection between the interior of member 176 and an annular groove 196 formed in the circumference of seat member 176. Another opening 198 is provided in the wall of reservoir 158 to connect said reservoir to groove 196 and thence to the bore of seat member 174 and through valve orifice 188 and passage 164 to cylinder 138. Fluid is introduced into reservoir 158 and replenished from time to time as necessary through a conventional oiler 200 mounted in the top wall of reservoir 158. A drainage opening, normally closed by threaded plug 202, is in communication with the groove 196 in member 176.

Operation

At the beginning of the cycle of operation necessary to grind threads on a work piece by means of the machine above described, the pocket 76 in control wheel 34 is positioned with its lower side below the top of work rest blade 24 and operating lever 96 is in its extreme counter-clockwise position, in contact with the upper stop lug 106. A work blank to be operated upon is placed in pocket 76 and manual rotation of operating lever 96 in a clockwise direction is begun. It will be apparent that rotation of operating lever 96 will cause the rotation of pinion 134 to which said lever is attached. The gear teeth of pinion 134 will coat with the rack teeth 140 on piston 136 to force said piston in a downward direction.

It will be understood that reservoir 158, the ends of cylinder 136 and the connecting passages have previously been filled with hydraulic fluid so that downward motion of piston 136 forces the fluid from the bottom end of cylinder 138 through channel 162 into passage 164. Since it is not possible for fluid to flow upwardly through passage 164 because of check valve 166, the fluid forced from cylinder 138 must proceed through the metering valve orifice 188, opening 194, groove 196 and opening 198 into reservoir 158. As before stated, the rate of this flow and therefore the speed of descent of piston 136 can be precisely regulated by the advance or withdrawal of metering valve stem 184.

Rotation of control wheel 34 in a clockwise direction causes the work piece to roll upwardly upon the inclined surface 28 of work rest blade 24 and to be brought into contact with the thread grinding ribs on grinding wheel 26. As peripheral section 80 of control wheel 34 is brought into contact with the work piece a strong torque is transmitted from the power driven grinding wheel through the work piece to the control wheel 34. The value of such force is dependent upon the amount of metal sought to be removed from the work piece. In case a finished thread is being ground from a solid cylindrical work blank, this force is of such severity that, without the use of the control mechanism above described, manual rotation of the control wheel is impossible and operating lever 96 is rapidly and violently rotated to its extreme clockwise position, sometimes with force sufficient to damage many of the machine elements.

However, since shaft 84 and pinion 134 must operate against the hydraulic resistance to move-

ment of piston 136, the force transmitted from grinding wheel 26 through the work piece to control wheel 34 is absorbed by the hydraulic pressure in the lower end of cylinder 138, so that the operating lever 96 may be manually rotated with ease. In this manner, it will be apparent that the effect of any driving torque from the grinding wheel upon the control wheel, having a value exceeding that required to manually oscillate the control wheel will be substantially nullified. It should be noted that, during the grinding operation, a vacuum in the upper end of cylinder 138 is prevented by the opening 160 which permits fluid to pass freely from reservoir 158 to cylinder 138.

When the rotation of control wheel 34 brings pocket 78 adjacent the top of work rest blade 24, the operating lever 96 strikes the lower stop lug 105 and the work piece drops into pocket 78. Operating lever 96 is then rotated counter-clockwise to return pocket 78 to loading position. During this portion of the work cycle, the operating lever 96 may be moved with the same facility as if the hydraulic mechanism were not used. This is the result of the partial vacuum created in the lower end of cylinder 138 by the upward movement of piston 136. As before described, fluid is thus freely drawn from reservoir 158 through the check valve and into the lower end of cylinder 138, equalizing the pressures at opposite ends of piston 136 so that control wheel 34 is easily returned to its starting position.

From the above it will be seen that by means of a mechanically simple and inexpensive addition to the manually operable machine of the Scrivener patent previously mentioned, the strong torque force which would otherwise be transmitted from the grinding wheel to the control wheel may be effectively neutralized or nullified so that the machine may be safely operated under high working pressures without danger of injury to the operator or damage to the machine parts. Also the invention provides a machine of this type which may be operated with great ease and facility to obtain maximum production of accurately finished work pieces.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a centerless grinding machine, a power driven grinding wheel, a control wheel in peripherally opposed relation to said grinding wheel to form a work grinding throat, drive means for said control wheel and additional means for substantially nullifying the transmission of driving torque exceeding a predetermined value, from the grinding wheel through the work piece to said control wheel.

2. A centerless grinding machine as defined in claim 1, wherein said additional means comprises a hydraulic torque neutralizer operatively connected with the control wheel.

3. A centerless grinding machine as defined in claim 1, wherein said additional means comprises a hydraulic torque neutralizer operatively connected with the control wheel, together with

means for variably regulating the effective response of said neutralizer to torque forces of different values.

4. In a centerless grinding machine, a power driven grinding wheel, an oscillatable control wheel in peripherally opposed relation to said grinding wheel to form a grinding throat, means for manually operating said control wheel, and means operatively connected with said last named means, responsive only to oscillation of the control wheel in grinding direction, to substantially nullify the transmission of driving torque exceeding a predetermined value from the grinding wheel through the work piece to said control wheel.

5. A centerless grinding machine as defined in claim 4, together with means for variably regulating the responsive action of said torque nullifying means in proportionate ratio to torque forces of different values.

6. In a centerless grinding machine, a power driven grinding wheel, an oscillatable control wheel in peripherally opposed relation to said grinding wheel to form a grinding throat, means for manually operating said control wheel, a relatively movable member operatively connected with said manual control wheel operating means, and means hydraulically controlling movement of said member in the manual oscillation of said control wheel in grinding direction, to nullify the driving effect upon the control wheel of torque force transmitted from the grinding wheel, having a value exceeding the manual torque force required to oscillate the control wheel.

7. A centerless grinding machine as defined in claim 6, wherein said hydraulic control means includes means operative in the reverse oscillation of the control wheel to render said hydraulic control means ineffective to influence movement of said member.

8. A centerless grinding machine as defined in claim 6, wherein said hydraulic control means includes a manually adjustable valve operable to variably control hydraulic resistance to movement of said member in proportionate ratio to the values of excessive torque forces.

9. In a centerless grinding machine, a power driven grinding wheel, an oscillatable control wheel in peripherally opposed relation to said grinding wheel to form a grinding throat, means for manually oscillating said control wheel, a cylinder, a reciprocable member in said cylinder operatively connected with said manual control wheel operating means, a reservoir for hydraulic medium and passages connecting opposite ends of the cylinder with said reservoir, and flow controlling valve means between one end of the cylinder and the reservoir producing hydraulic resistance to movement of said member in response to torque forces on the control wheel exceeding the value of the manual torque force required to oscillate said wheel in work grinding direction.

10. A centerless grinding machine as defined in claim 9, wherein said valve means includes a spring seated check valve preventing fluid flow from said cylinder end into the reservoir, a bypass around said valve, and a metering valve in said bypass for variably regulating resistance of the hydraulic medium to movement of said reciprocable member.

11. In a centerless grinding machine, a work control wheel selectively operable by power driven or manually operative means, said latter means comprising a rotatable and axially movable shaft, independently operable means for rotating and

axially shifting said shaft, means for releasably establishing a driving connection between said shaft and the control wheel by axially shifting said shaft, an energizing unit for the power driven means, and means operable by said shaft to effectively actuate said energizing unit in the axial movement of said shaft to disconnect the same from the control wheel.

12. A centerless grinding machine as defined in claim 11, wherein said energizing unit comprises a normally open electric switch, and said actuating means comprises a member fixed to the shaft directly actuating and holding said switch in circuit closing position.

13. A centerless grinding machine as defined in claim 11, wherein said last named means is fixed to one end of said shaft and a manually operable lever for rotating said shaft is fixed to the opposite end thereof.

14. A centerless grinding machine as defined in claim 11, wherein the means for axially shifting said shaft comprises a manually operable member mounted to rotate upon an axis normal to the shaft axis and having means coacting with means on said shaft to impart axial movement thereto while permitting free rotation of said shaft.

15. A centerless grinding machine as defined in claim 11, wherein the means for axially shifting said shaft comprises a manually operable member mounted to rotate about an axis normal to the shaft axis, said member having an eccentrically offset stud projecting from one end thereof and coacting with spaced annular parts on said shaft upon rotation of said member to axially shift the shaft in each direction.

16. In a centerless grinding machine, a power driven grinding wheel, a control wheel peripherally opposed to said grinding wheel to form a work grinding throat, and a hydraulic torque neutralizing unit operatively connected to said control wheel to substantially nullify the transmission of driving torque exceeding a predetermined value from the grinding wheel through the workpiece to the control wheel.

17. The combination defined in claim 16, together with means for variably regulating the responsive action of said torque neutralizing unit in proportionate ratio to torque forces of different values.

18. The combination defined in claim 16, wherein said torque neutralizing unit includes means automatically operative to render said unit functionally inactive upon rotation of the control wheel relative to the grinding wheel when the latter wheel is not in grinding contact with a work piece.
